UNITED STATES PATENT OFFICE.

CHARLES D. KNIGHT, OF SCHENECTADY, NEW YORK, ASSIGNOR TO GENERAL ELECTRIC COMPANY, A CORPORATION OF NEW YORK.

RHEOSTAT.

No. 882,569.

Specification of Letters Patent. Patented March 24, 1908.

Application filed July 18, 1907. Serial No. 384,464.

To all whom it may concern:

Be it known that I, CHARLES D. KNIGHT, a citizen of the United States, residing at Schenectady, county of Schenectady, State 5 of New York, have invented certain new and useful Improvements in Rheostats, of which the following is a specification.

This invention relates to devices for controlling electric motor circuits and has for its 10 object the provision of a device of this character in which the motor will be controlled to a predetermined point in a reliable and simple manner.

My invention relates more specifically to 15 combined starting and speed regulating rheostats in which the motor is first brought up to running speed and the speed then varied within certain limits.

One of the objects of my invention is to 20 provide means whereby a positive limit is placed upon the speed at which the motor is to be operated while at the same time providing for the variation of this limit. I also provide means whereby the setting of the 25 limit is beyond the control of the operator, the arrangement being such that the adjusting feature is locked by a key which is not accessible to the operator.

In carrying out my invention I provide in 30 connection with starting and speed controlling resistance, a controlling arm which is biased to starting position. A fixed retaining magnet is provided to coöperate with the armature on the controlling arm in the 35 usual way. This armature is made adjustable and is locked in various positions by means of a key. In this way the arm may be held by the retaining magnet in various positions on the controlling resistance so that 40 a definite speed may not be departed from.

In the accompanying drawing, in which I have shown my invention embodied in a concrete form, Figure 1 is a plan view of the device showing the diagram of circuits; and 45 Fig. 2 shows the locking device for the armature.

Referring to the drawing, 10 is an insulating base of slate or soapstone provided with a series of contacts 11, forming terminals of 50 starting resistance 12, and a series of contacts 13 for the speed controlling resistance 14. The contacts are concentrically arranged so as to be successively engaged by a controlling arm, 15 pivoted at 16. This arm is

spring-pressed to the off position, as shown 55 in full lines, by means of the spring 17. A segment 18 is arranged adjacent to contacts 11 and a similar segment 19 is arranged adjacent to contacts 13. An armature 20 is pivoted to the arm 15 so as to engage the 60 poles of the retaining magnet 21 in the usual way. The armature instead of being permanently fixed to the arm is made adjustable by being pivoted to a curved bracket 22 provided with a slot 23. A locking stud or 65 bolt 24 passes through the slot and screws into the arm 15. By tightening this stud the bracket is held in a fixed position. A key or socket wrench 25 is adapted to fit the head of the stud 24 so as to adjust the same. 70

The arrangement of circuits and the mode of operation are as follows: When it is desired to start the motor, the arm 15 is moved to the right over the contacts 11 thereby cutting out the resistance 12. The armature 75 circuit will now be as follows: from the + main through the armature A, conductor 26, segment 19, resistance 12 and arm 15 back to the — main, the field circuit being completed from the armature through the field F, conductor 27, segment 18, arm 15 and back to the — main. When the arm passes off the last stud 11 on to the segment 19, all of the starting resistance is cut out and the motor is running at its lowest speed. By moving the 80 arm farther it passes on to the studs 13, and the resistance 14 is thereby inserted in the field circuit, increasing the speed of the motor. The movement is continued until the armature 20 engages with the magnet 21 90 where it is held. By adjusting the armature 20 along the arm, the point at which the speed of the motor must be operated will be varied. The armature may be set by someone in charge of the work being done, as for 95 instance the foreman, and the key removed. The speed at which the motor will run is thus beyond the control of the operator. The magnet 21 may be connected across the line, as shown, and a short-circuiting switch 28 100 provided for short-circuiting the magnet and stopping the motor by allowing the controlling arm to go to the off position.

It will be seen that I have provided a very simple and convenient arrangement whereby 105 the motor may be started and the speed varied within certain limits. The speed at which the motor is run is taken out of the

hands of the operator so that the person in charge always knows that the motor is being run at the desired speed.

It will be understood, of course, that various modifications will suggest themselves to those skilled in the art without departing from the spirit of my invention, the scope of which is set forth in the annexed claims.

What I claim as new and desire to secure by Letters Patent of the United States, is—

1. A rheostat for electric motors comprising a resistance, a controlling arm therefor, a retaining magnet for said arm, and an armature for said magnet adjustably mounted upon the arm.

2. A rheostat for electric motors comprising a resistance, a retaining magnet, a controlling arm having an armature coöperating with said magnet, and means for locking said armature in various positions on the arm.

3. A rheostat for electric motors comprising a starting resistance and a field resistance, a controlling arm therefor, a retaining magnet for said arm, and an armature for said magnet adjustably mounted upon the arm.

4. A rheostat for electric motors comprising a resistance, a controlling arm therefor, a retaining magnet for said arm, an armature for said magnet adjustably mounted upon the arm, and a key for locking the armature in various positions. 30

5. A rheostat for electric motors comprising a starting resistance and a field resistance, a controlling arm therefor, a retaining magnet for said arm, an armature for said magnet adjustably mounted upon the arm, and a key for locking the arm in various positions. 35

6. A motor starter comprising starting and field resistance, a spring controlled arm co-operating therewith, a release magnet responsive to predetermined circuit conditions, and means for retaining the arm in operative relation to the magnet in different positions 45 of field adjustment.

In witness whereof, I have hereunto set my hand this 16th day of July, 1907.

CHARLES D. KNIGHT.
